UNITED STATES PATENT OFFICE

140,110

DESIGN FOR A LUMINOUS LAMP SHADE

James Ross, Hubbard Woods, Ill.

Application October 20, 1944, Serial No. 115,892

Term of patent 14 years

(Cl. D48—16)

To all whom it may concern:

Be it known that I, James Ross, a citizen of the United States, residing at Hubbard Woods, in the county of Cook and State of Illinois, have invented a new, original, and ornamental Design for a Luminous Lamp Shade, of which the following is a specification, reference being had to the accompanying drawing, forming a part thereof.

Fig. I shows a perspective view of the luminous lamp shade embodying my design.

Fig. II is a vertical section of Fig. I.

I claim:

The ornamental design for a luminous lamp shade, substantially as shown.

JAMES ROSS.
